United States Patent Office

Des. 206,866
Patented Feb. 7, 1967

206,866

AUXILIARY BUILDING

Eliot F. Noyes, New Canaan, and Arthur De Salvo, Jr.,
Norwalk, Conn., assignors to Mobil Oil Corporation, a
corporation of New York

Filed Mar. 21, 1966, Ser. No. 1,580

Term of patent 14 years

(Cl. D13—1)

FIG. 3

FIG. 4

FIG. 5.FIGURE 1 is a front view of the auxiliary building of our new design.

FIGURE 2 is a rear view of the building of FIGURE 1.

FIGURE 3 is a left side view of the building of FIGURE 1.

FIGURE 4 is a right side view of the building of FIGURE 1.

FIGURE 5 is a cross-sectional view of the building shown in FIGURE 1 taken on line 5-5 thereof.

We claim:

The ornamental design of an auxiliary building, as shown and described.
